(57) CLAIM

The ornamental design for a business card holder, as shown and described.

DESCRIPTION

FIG. 1 is a perspective view of a business card holder showing my new design;

FIG. 2 is a top plan view thereof;

FIG. 3 is a left side elevational view thereof;

FIG. 4 is a front elevational view thereof;

FIG. 5 is a right side elevational view thereof;

FIG. 6 is a rear elevational view thereof;

FIG. 7 is a bottom plan view thereof; and,

FIG. 8 is a second perspective view thereof.

The indicia and the business card depicted by means of broken lines in the figures have been shown for illustrative purposes only and form no part of the claimed design.
